UNITED STATES PATENT OFFICE.

JOSEPH WARBASSE, OF NEWTON, NEW JERSEY.

RESPIRATOR.

No. 812,706.

Specification of Letters Patent.

Patented Feb. 13, 1906.

Application filed August 3, 1904. Serial No. 219,817.

To all whom it may concern:

Be it known that I, JOSEPH WARBASSE, a citizen of the United States, and a resident of Newton, in the county of Sussex and State of New Jersey, have invented a new and Improved Respirator, of which the following is a full, clear, and exact description.

This invention relates to improvements in respirators, an object being to provide a device of this character that will be very light, and therefore adapted to be conveniently worn over a person's nose to supply out-of-door air to invalids or other persons requiring pure air during waking or sleeping hours, the device being also adapted for use in laboratories, shops, and other places where noxious fumes, filings, fine dust, or the like floating in the air are liable to be inhaled. The device will also be found useful for the administration of oxygen, gas, anesthetics, medicated air, and vapors.

Other objects of the invention will appear in the general description.

I will describe a respirator embodying my invention and then point out the novel features in the appended claim.

Reference is to be had to the accompanying drawings, forming a part of this specification, in which similar characters of reference indicate corresponding parts in all the figures.

Figure 1 is a front view of a respirator embodying my invention showing the same in position. Fig. 2 is a sectional elevation of the device, and Fig. 3 is a section on the line 3 3 of Fig. 2.

The respirator comprises a shield or mask 5 designed to be placed over a person's nose and conforming substantially thereto. The inner edge of the bottom wall is curved 40 and provided with a downwardly-extended flange, as indicated at 6. This curved portion is designed to engage over the lip just below the nose, leaving the mouth free. The rear edge of the respirator is provided with a suitable packing 7, which will bear sufficiently close against a person's face to prevent the inlet or outlet of air or the like.

The device is held in position by means of an elastic cord or tape 8, secured at one end 50 to one side of the respirator and adapted to engage at the other end with a hook 9; but other means for securing the device in position may be employed without departing from the spirit of my invention. When the elastic 55 is used, however, the same will be passed over

and under the ears, as plainly indicated in Fig. 1. At the front of the respirator is an opening 10, and outward of this opening is a hood 11, which is open at the bottom, the said hood being inclined downward and outward and fully inclosing the valve. Arranged within the hood 11 and adapted to control the outlet 10 is a valve 12, which is in the form of a flap-valve, preferably consisting of thin rubber, so that it will readily open 65 and close.

In the upper wall of the respirator is an inlet-opening 13, controlled by an inwardly-opening flap-valve 14 of similar construction to the outwardly-opening valve 12. 70 Connected to the upper wall of the respirator and communicating with the inlet 13 is a short tube 15, which may consist of any suitable light material—such, for instance, as thin aluminium—and it is to be understood 75 that the body of the respirator and the hood 11 may also be made of the same material. Connected to the tube 15 is a flexible tube 16, designed to be passed to the open air—such, for instance, as through an opening in a window-sash, as indicated in the drawings—or through an opening in a window-casing or the like or to a connection with a large air-conduit when used in common in the same room by many persons—as, for instance, in factories, &c.

To prevent lateral motion of the flexible tube, which might disarrange the respirator, I may employ a head band or cap 17, designed to be placed on a person's head and 80 having metal clips 18 for engaging with the flexible tube.

When the device is in use, as a person inhales the valve 12 will close and prevent the drawing into the lungs of any air except 95 through the external supply-tube 16, and the inlet-controlling valve prevents the supply-tube from being filled with expired air and re-breathed. The valves being very light will operate noiselessly, which is a very essential 100 feature, especially when the device is worn by a sleeping person.

Having thus described my invention, I claim as new and desire to secure by Letters Patent—

A respirator comprising a nose-mask, the inner edge of the lower wall being curved and provided with a downwardly-extended flange, the said mask having inlet and outlet openings, valves for said openings, a hood 110

over the outlet-opening and open at the bottom the said hood being inclined downward and outward and fully inclosing the valve, a short tube communicating with the inlet, and 5 a flexible tube extending from said short tube.

In testimony whereof I have signed my

name to this specification in the presence of two subscribing witnesses.

JOSEPH WARBASSE.
